SADIRON CONSTRUCTION

Russell I. Huffman, Dover, Ohio, assignor to
 Knapp-Monarch Company, St. Louis, Mo., a
 corporation of Missouri

Application April 9, 1941, Serial No. 387,595

8 Claims. (Cl. 219—25)

My present invention relates to a sad iron construction, particularly with respect to a simple and inexpensive means for connecting a shell to a baffle plate of the iron.

A further object is to provide such connecting element with hooked notch and lug means of engagement with the baffle plate so that after the baffle plate is secured in position on the sole plate and covering the heating element countersunk in the sole plate, the connecting element may be slid longitudinally of the iron to a position of coaction of the hooked notch and lug means and thereafter a shell for the sad iron may be secured to the connecting element and the connecting element and shell are both thereby retained in assembled position against any possible dislodgment.

Another object is to provide the connecting element with a central opening to provide clearance for a temperature indicator depending from the shell of the iron or for a thermostat adjusting screw extending down to a thermostat countersunk in a socket of the sole plate.

With these and other objects in view, my invention consists in the construction, arrangement and combination of the various parts of my device whereby the objects contemplated are attained, as hereinafter more fully set forth, pointed out in my claims and illustrated in the accompanying drawings. Although the invention is susceptible of a variety of embodiments, it is unnecessary to fully describe more than one in order to give a full understanding of the invention both from its structural and functional standpoints. Accordingly, I have illustrated a preferred and desirable embodiment of the invention in the accompanying drawings, in which:

Figure 1 is a longitudinal sectional view through a sad iron showing my invention applied thereto, a connecting element of the invention being shown in side elevation;

Figure 2 is a horizontal sectional view on the line 2—2 of Figure 1 showing a plan view of the sole plate and the baffle plate mounted thereon;

Figure 3 is a sectional view on the line 3—3 of Figure 1;

Figure 4 is a perspective view of a connecting element of my structure as viewed from the bottom;

Figure 5 is a sectional view similar to Figure 1, showing a slightly modified connecting element;

Figure 6 is a sectional view on the line 6—6 of Figure 5, and

Figure 7 is a perspective view of the connecting element of Figure 5 and the portion of a

baffle plate with which it, in the form of connecting element shown in Figure 4, cooperates.

On the accompanying drawings, I have used the reference numeral 10 to indicate a sole plate 5 and 12 a heating element countersunk therein. A baffle plate 13 is secured to the sole plate 10 as by screws or headed pins 14 pressed into openings 15 of the sole plate. The baffle plate 13 retains the heating element 12 in position and reflects heat therefrom toward the lower surface of the sole plate 10.

The baffle plate 13 has a pair of upstanding flanges 16 and 17 which are perhaps best shown in Figure 7. The flange 16 has a pair of notches 18 which are hooked, the hook members being indicated at 19. Similarly, the flange 17 has a notch 20 hooked as at 21.

A connecting element C is adapted to coact with the hooked notches 18 and 20. Two of 20 the connecting elements C and C' are illustrated in Figure 4 and Figure 7, respectively. Each connecting element has a web 22 and a pair of flanges 23 and 24. The flange 23 is provided with a pair of outstanding lugs 25, while the flange 24 is provided with a single outstanding lug 26. Each web 22 is provided with a pair of threaded openings 27 and with a central opening 28 for the connecting member C and 28^a for the connecting member C'.

The opening 28 is adapted to provide clearance for a temperature indicator 29, as shown in Figure 1, while the threaded openings 27 of the connecting member C are adapted to receive hold-down screws 30 for a shell 31 of the sad 33 iron. The screws 30 may also retain handle supporting straps 32 of a handle 33 in position.

During assembly of the connecting member C, the lugs 25 and 26 are introduced in a rearward direction into the slots 18 and 20 which are open 40 at their forward ends. The connecting member is then pushed rearwardly as far as it will go and when it is then lifted the lugs 25 and 26 assume a position behind the hooks 19 and 21 so that insertion of the hold-down screws 30 will retain the connecting member in its raised position, as shown in Figure 1, and it cannot thereafter shift forwardly with respect to the sole plate. Thus the connecting member may be quickly assembled in its proper position and is thereafter retained by the hold-down screws, while the hold-down screws also effect retention of the shell 31 in its assembled position with its lower edge contacting the upper surface of the sole plate.

The central opening 28^a of the connecting

member C' is provided for a thermostat adjusting screw 34, as shown in Figure 5. The thermostat itself is indicated generally by the reference character T and is countersunk in a socket 35 of the sole plate 10. After the connecting member C' is associated with the hooked notches 18 and 20, the adjusting screw 34 is inserted. Thereafter, hold-down screws 30 are screwed into the openings 27 for holding the shell 31 in position, as illustrated in Figure 5. Thereafter a knob 36 may be mounted on the thermostat adjusting screw 34 for changing the adjustment thereof.

From the foregoing description, it will be obvious that I have provided a simply constructed connecting element for a sad iron shell with respect to a baffle plate of the sad iron. The connecting element may be readily associated with the baffle plate without the use of screws or other connecting elements and the hold-down screws for the shell of the iron, when inserted, serve the purpose of holding the connecting element against dislocation from its assembled position.

Some changes may be made in the construction and arrangement of the parts of my device without departing from the real spirit and purpose of my invention, and it is my intention to cover by my claims any modified forms of structure or use of mechanical equivalents which may be reasonably included within their scope without sacrificing any of the advantages thereof.

I claim as my invention:

1. In a sad iron construction, a sole plate, a heating element therein, a baffle plate secured to said sole plate for covering said heating element, said baffle plate having a centrally located opening elongated in a fore and aft direction, said opening providing clearance for a thermostat countersunk in a socket in said sole plate, said baffle plate having upstanding flanges adjacent the sides of said opening, said flanges having downwardly hooked notches, a connecting element of channel shape having out-turned lugs on its flanges for reception in said notches by sliding longitudinally of the iron, said connecting element having an opening to receive a thermostat adjusting screw and having a pair of threaded openings in its web, a shell for said sole plate, and hold-down screws for said shell extending into said threaded openings.

2. In a sad iron construction, a sole plate, a heating element therein, a baffle plate secured to said sole plate for covering said heating element, said baffle plate having a centrally located opening and upstanding flanges adjacent the edges thereof, said flanges having notches therein, a connecting element of channel shape having out-turned lugs on its flanges for reception in said notches and having a threaded opening in its web, a shell for said sole plate, and a hold-down screw for said shell extending into said threaded opening.

3. In a sad iron construction, a sole plate, a heating element therein, a baffle plate secured to said sole plate over said heating element, said baffle plate having an opening elongated in a fore and aft direction and having upstanding flanges adjacent the sides of said central opening, a con-

necting element of channel shape having its flanges engaged with the flanges of said baffle plate and having a threaded opening in its web, a shell for said sole plate, and a hold-down screw for said shell extending into said threaded opening.

4. A sad iron construction comprising a sole plate, a baffle plate secured thereto, said baffle plate having upstanding flanges provided with downwardly hooked notches, a connecting element of channel shape having out-turned lugs on its flanges for reception in said notches, a shell for said sole plate, and means for connecting said shell to the web of said connecting element and drawing the shell toward the sole plate.

5. In a sad iron construction, a sole plate, a heating element therein, a baffle plate secured to said sole plate and covering said heating element, said baffle plate having upstanding flanges longitudinally arranged thereon, said flanges having notches therein, a connecting element of channel shape having out-turned lugs on its flanges for reception in said notches by sliding longitudinally of the iron, a shell for said sole plate, and hold-down screws for connecting said shell to the web of said connecting element.

6. In a sad iron construction, a sole plate, a heating element therein, a baffle plate secured to said sole plate for retaining said heating element therein, said baffle plate having an opening and upstanding flanges adjacent the edges of said opening, said flanges having downwardly hooked notches, a connecting element of channel shape having out-turned lugs on its flanges for reception in said notches, said connecting element having an opening to receive a temperature indicator and having a pair of threaded openings in its web in front of and behind said last opening, a shell for said sole plate, a temperature indicator supported thereby and depending therefrom into said opening of said connecting element, and hold-down screws for said shell extending into said threaded openings.

7. A sad iron construction comprising a sole plate, a baffle plate secured to said sole plate and having upstanding flanges, said flanges having notches, a connecting element having lugs for reception in said notches, said connecting element having an opening to receive a temperature indicator, a shell for said sole plate, a temperature indicator supported thereby and depending therefrom into said opening of said connecting element, and means for connecting said shell with said connecting element.

8. In a sad iron construction, a sole plate, a baffle plate, means for securing said baffle plate to said sole plate, said baffle plate having an opening elongated in a fore and aft direction and having a pair of upstanding flanges along the sides of said opening, one of said flanges having a pair of notches and the other one having a single notch, a connecting element of channel shape having a pair of lugs on one of its flanges and a single lug on its other one for reception in said notches of said baffle plate flanges, a shell for said sole plate, and means for securing said shell to the web of said connecting element.

RUSSELL I. HUFFMAN.
